CLAIM

The ornamental design for a pendant or the like, substantially as shown and described.

DESCRIPTION

FIG. 1 is a front elevational view of pendant or the like showing my new design, the rear elevational view being substantially a mirror image thereof;

FIG. 2 is an elevational view of one side of said pendant or the like, the elevational view of the other side being substantially a mirror image thereof; and

FIG. 3 is an end view of said pendant or the like, the other end view of said article of jewelry being substantially a mirror image thereof.
